TUYÈRE CONSTRUCTION FOR COAL-BURNING STOKERS

Cornell Carlson and Eugene M. Rosen, Chicago, Ill., assignors, by direct and mesne assignments, of one-fourth to Beatrice J. Carlson, and one-fourth to George L. Coffey, both of Chicago, Ill.

Application May 18, 1939, Serial No. 274,344

7 Claims. (Cl. 122—374)

The present invention pertains to or relates to certain features of improvement and advantage in the tuyère-tops of stoker-fed coal-burning retorts, such as are commonly used in connection with steam-boilers or hot-water boilers, etc., and warm air furnaces.

In constructions of this type, as at present employed, trouble is more or less commonly encountered by reason of the objectionable nature of the clinkers formed by the burned coal and which clinkers must be periodically removed from the fire-chamber of the furnace.

Not infrequently, the clinker forms in such a way as to close some of the air-ports, thus seriously interfering with the proper operation of the retort, and, in some cases, causing a melting of important and essential parts of the structure and, in other instances, effecting fusion of the clinker to the retort.

Again, in such retorts of the prior art, it is impossible, for several reasons, to burn satisfactorily the lower grades of coal.

Accordingly, one of the outstanding and paramount aims of the present invention is to provide a novel and improved retort structure which overcomes the specified and other structural and functional defects of the retorts now in general use.

Our improvements comprise two principal features (a) the cooling of the tuyère-top of the retort by the circulation therethrough of water from the associated boiler, thus preventing such top from heat damage, and, at the same time, improving or augmenting the circulation of the water in the boiler, resulting in bettered and more efficient heating of the water in the boiler and a less frequent operation of the associated stoker, and (b) the directing of the air-jets issuing from the tuyère into the coal in such a manner as to produce a circulation of the discharged air in one direction inside of the retort and in the opposite direction outside of the retort, which action, especially when combined with the cooling of the tuyère-top in the manner specified, allows efficient and satisfactory burning of the lowest grades of fuel.

By thus internally cooling the tuyère-top of the retort, the lower constant temperature assures the impossibility of the tuyère-member, or any part of the retort, from becoming unduly heated or damaged or injured by the heat.

Again, with the new structure, the clinker-forming material will not fuse to the burner or tuyère-top, the occurrence of which would neces-

sitate poking and pounding for the removal of the clinker, this being one of the major reasons for present-day burner and tuyère failures.

Further, burn-back is wholly avoided in the new construction because the latter allows coking of the coal in a modified state only, and, as the fuel is fed upwardly mechanically, the temperature of the fuel is maintained below that of ignition until the coal reaches the fire-line or air-ports, this feature also preventing a smoke-back in the hopper, and, at the same time, eliminating the coke-tree in large degree, but rather maintaining a substantially-level fire-bed.

Additionally, our newly designed or modified arrangement and configuration of parts precludes the locking or termination of the operation of the retort and its complementary or associated fuel-feeding stoker, which seriously objectionable occurrence takes place if the clinker is allowed to melt and run back into the retort while the stoker is working, and then, when the stoker ceases operation temporarily, such clinker hardens or solidifies in the retort, and thereafter, when the stoker again attempts to function, the coal-feed is blocked or locked, causing the shear-pin to break, or the clutch to be thrown out, resulting in extinguishment of the fire, and the stoker remains in such inoperative condition, the air being blown uselessly, until the clinker is pounded out of the retort with more or less difficulty and the shear-pin renewed.

Moreover, inasmuch as the air-delivery ports or passages circulate the air in the retort and outside of it in opposite directions, each in a more or less cyclonic action, the combustion of the fuel is materially aided, and the rotary action of the air in the retort whirls the molten slag to the top of the cooled tuyère, forming thereon a doughnut-like clinker which can be removed with a minimum of effort and time and with no disturbance to the burning fuel.

To enable those acquainted with this art to understand the present invention fully, both from structural and functional standpoints, a present preferred embodiment thereof has been illustrated in detail in the accompanying drawing, to which reference should be had in connection with the following description, and, for simplicity, like reference numerals have been employed in the views to designate the same structural parts.

In this drawing:

Figure 1 is a central vertical section through the structure; and

Figure 2 is a view of the underside of the tuyère-top of the retort.

The fuel-retort includes a round, somewhat upwardly-flaring coal-conduit 10 up through which the fuel is gradually fed, usually intermittently automatically, by means of a feed-screw 11 actuated or rotated by an electric-motor, not shown, the upper part of the retort having a pair or plurality of upwardly-flaring rings 12 and 13, the former resting on the top of member 10 and the companion one 13 bearing on the underlying ring 12.

Each such ring on its under surface is equipped with a number of radial ribs on which the ring is supported, such ribs providing between them a corresponding series of radial-passages characterized 14 for ring 12 and 15 for ring 13.

In order to maintain these rings in position, the upper outer margin of the member 10 has a circular rib 16 inside of which the ribs of ring 12 fit, and the upper outer margin of ring 12 has an upstanding circular rib 17 which accommodates inside of it the ribs of the upper ring 13.

Surrounding and spaced from these superposed members 10, 12, and 13 is a suitably-supported cylindrical housing or casing 18 having on its under side a small number of vertically-apertured bosses 19, only one of which is shown, and the holes through which each accommodates a stud or bolt 21 fitted in a hole in a corresponding projection or extension 22 outstanding from the external surface of member 10, the head 23 on the lower end of such securing member 21 maintaining or holding member 10 in place, the top ends of such screws or bolts being received in screw-threaded holes in the lower part of the novel, annular, tuyère, retort-top member 24, thereby also keeping the latter fixedly in position.

This tuyère-member 24 has a circular channel or groove 25 in its bottom face and such annular recess receives in it, a round, upright, centering rib 26 on the inner portion of the top end of casing 18, the element 18 solely supporting and carrying the part 24, all as is fully and clearly illustrated.

As is indicated in Figure 2, the bottom face of the ring-shaped top 24 is provided with a series of spaced, inwardly-directed, oblique passages 27, 27 cut deeper into the bottom of the member than its circular channel 25 and directly communicating with such channel and with the open center of such ring-shaped top member.

As is depicted, these passages are not radial with respect to the center of element 24, but all of them aim to one side of such center so that the conjoint action of the plurality of air-jets issuing from the passages under pressure create a cyclonic effect or whirlwind of air in one circular direction around the center of such top, in the present instance counterclockwise in direction.

The underside of such tuyère-member 24 is supplied also with a circular series of outwardly-directed oblique passages 28, 28 connecting groove 25 with the exterior of the top, such passages being non-radial and equally oblique, whereby air issuing therefrom under pressure creates a whirlwind around the outside of the retort in a clockwise direction of circulation the reverse of that of the inside whirlwind referred to above.

Air under pressure, as from a fan or air-compressor (not shown), is fed through conduit 29 and up through the annular space between the members 10 and 18 into groove 25 from which it is discharged through the two sets of delivery

passages 27 and 28 to produce the two reversely-revolving whirlwinds inside and outside of the tuyère-ring, some of the air before reaching such groove or channel 25 being delivered into the fuel in the retort through the passages 14 and 15.

The retort tuyère-top 24 is hollow having within it the circular conduit or passage 31 connected through the bottom wall thereof by a water inlet-pipe 32 to the interior of the lower portion of the boiler (not shown) with which the fuel-burning retort is associated, whereby water of relatively low temperature is fed from the lower part of the boiler into such passage 31.

Such cooling water, after flowing around the inside of the tuyère-top through conduit 31 in two paths in parallel arrangement, is discharged back into the boiler at a higher level through a second pipe 33 connected to the side of passage 31 at a point diametrically opposite the position where pipe 32 delivers its water thereto.

The specified flow of water is occasioned by a thermo-syphon action of well-understood principles, the water cooling the tuyère-top and itself becoming heated and returned to the boiler at such raised temperature.

Thus the water cools the tuyère-element and augments or increases the water-circulation in the boiler with direct beneficial results, in fact, increasing the heating capacity of the boiler.

From what precedes, it will be apparent that the water-cooling referred to, combined with the two whirlwinds of air, prevents the clinker-forming material from flowing down the tuyère-top and closing the air-delivery ports, and their united actions cause the clinker to form above the tuyère-top in ring-shape, and of such character that it can be readily removed periodically.

The new construction, because of such novel action, allows the satisfactory burning of low grades of fuel which in many instances is of material advantage and of substantial importance from an economic aspect.

Those skilled in this art will readily understand that the present invention is not necessarily limited to the details of construction herein presented and that the construction may be modified within reasonable limits without departure from the heart and essence of the invention as defined by the appended claims and without the loss or sacrifice of its substantial benefits and advantages.

It may be understood that the stoker-fed coal-burning retort is not new except insofar as the tuyère-member or air-delivery top and its water-connections are concerned.

Whereas, we have shown and described the use of water for cooling the tuyère-top of the retort, it is to be understood that air under pressure may be used instead for the same purpose, and, in the case of hot-air furnaces, the air heated by flowing through such top may be delivered into the air-circulating current of the heating-system.

We claim:

1. In a tuyère-top for a stoker-fed coal-burning retort, said retort and top when combined having registered central openings up through which the fuel is fed, such fuel passing over said top and down around the outer side thereof, said top having means therein to receive air under pressure and a series of outwardly-directed air-discharge passages delivering the air into the coal surrounding the retort and tuyère-top, the novel feature of the oblique-arrangement of said passages to cause conjointly a whirlwind circula-

tion of their delivered air around the retort and top.

2. In a tuyère-top for a stoker-fed coal-burning retort, said retort and top when combined having registered central openings up through which the fuel is fed, said top having means therein to receive air under pressure and a series of inwardly-directed air-discharge passages delivering the air into the coal in the retort and tuyère-top, the novel feature of the oblique-arrangement of said passages to cause conjointly a whirlwind circulation of their delivered air around the interior of the retort and top.

3. In a tuyère-top for a stoker-fed coal-burning retort, said retort and top when combined having registered central openings up through which the fuel is fed, such fuel passing over said top and down around the outer side thereof, said top having means therein to receive air under pressure, a series of inwardly-directed air-discharge passages delivering the air into the coal in the retort and tuyère-top, and a second series of outwardly-directed air-discharge passages delivering the air into the coal surrounding the retort and tuyère-top, the novel features of the oblique-arrangements of said passages of both series to cause whirlwind circulations of their delivered air in and around the retort and top, said two whirlwind circulations being in reverse directions.

4. The tuyère-top set forth in claim 1 which is hollow to form a cooling-water conduit therein, in combination with the novel features of a first pipe connecting one portion of said conduit to the interior of the associated boiler to receive water from the latter and a second pipe connecting another portion of said conduit to the interior of the boiler at a higher level than the corresponding connection therewith of said first pipe, whereby the water flowing from the boiler and then back to the boiler through said pipes and conduit cools said tuyère-top and increases the water-circulation in the boiler.

5. The tuyère-top set forth in claim 2 which is hollow to form a cooling-water conduit therein, in combination with the novel features of a first pipe connecting one portion of said conduit to the interior of the boiler heated by the fuel burning in said retort to receive water from said

boiler and a second pipe connecting another portion of said conduit to the interior of said boiler at a higher level than the corresponding connection therewith of said first pipe, whereby the water flowing from said boiler and then back to the boiler through said pipes and conduit cools said tuyère-top and increases the water-circulation in the boiler.

6. The tuyère-top set forth in claim 3 which is hollow to form a cooling-water conduit therein, in combination with the novel features of a first pipe connecting one portion of said conduit to the interior of the associated boiler to receive water from the latter and a second pipe connecting another portion of said conduit to the interior of the boiler at a higher level than the corresponding connection therewith of said first pipe, whereby the water flowing from the boiler and then back to the boiler through said pipes and conduit cools said tuyère-top and increases the water-circulation in the boiler.

7. In a tuyère-top for a stoker-fed coal-burning retort, said retort and top having registered central openings up through which the fuel is fed, said top having means to receive air under pressure, and a series of air-discharge passages delivering such air from the top into the fuel, said tuyère-top being hollow to provide a water-conduit therein, the novel features of such conduit being in endless form and in combination with an inlet-pipe connected to the interior of said conduit through the bottom-wall of said top and to the interior of the boiler heated by the fuel burning in said retort and top to convey water from said boiler to said conduit, and a discharge-pipe connected to the interior of said conduit through the side-wall of said top and at a distance around said top from said inlet-pipe connection therewith and connected to the interior of said boiler at a higher level than the corresponding connection therewith of said inlet pipe, whereby water flowing from said boiler through said inlet pipe passes through said tuyère-top conduit in streams in parallel relation and returns to the boiler through said discharge pipe, thus cooling said tuyère-top and increasing the water circulation in the boiler.
